BOTTLE

John B. Rosefield, Piedmont, Calif.

Application June 11, 1953, Serial No. 25,455

Term of patent 14 years

(Cl. D58—11)

To all whom it may concern:

Be it known that I, John B. Rosefield, a citizen of the United States of America, residing in the city of Piedmont, county of Alameda, State of California, have invented a new, original, and ornamental Design for a Bottle, of which the following is a specification, reference being had to the accompanying drawing, forming a part hereof, and in which:

I claim:

The ornamental design for a bottle, as shown.
JOHN B. ROSEFIELD.
